DESIGN FOR A TEXTILE FABRIC OR SIMILAR ARTICLE

Application filed June 14, 1929. Serial No. 31,694. Term of patent 3½ years.

To all whom it may concern:

Be it known that I, FRIEDA B. PAISNER, a citizen of the United States, and a resident of New York city, borough of Brooklyn, in the county of Kings and State of New York, have invented the new, original, and ornamental Design for a Textile Fabric or Similar Article, of which the following is a specification, reference being had to the accompanying drawing, forming a part thereof.

The figure on the drawing is a plan view of a piece of textile fabric bearing my new design which is intended to be carried for-

ward or repeated ad libitum, as shown. The shading is on the drawing only to indicate more or less contrasting colors and not to indicate specific colors.

A single unit of my design is substantially comprised within the area defined by the indicating arrows shown on the drawing, which arrows form no part of the design.

I claim:

The ornamental design for a textile fabric or similar article substantially as shown and described.

FRIEDA B. PAISNER.
